UNITED STATES PATENT OFFICE

HERMANN HUFNER, OF NEW YORK, N. Y.

DESIGN FOR AN AQUARIUM

Application filed August 13, 1930. Serial No. 36,661. Term of patent 3½ years.

To all whom it may concern:

Be it known that I, HERMANN HUFNER, a citizen of Germany, residing in New York, in the county of New York, in the State of New York, have invented a new, original, and ornamental Design for an Aquarium, of which the following is a specification, reference being had to the accompanying drawing, forming a part thereof.

The figure is a perspective view of the aquarium, showing my new design.

I claim:

The ornamental design for an aquarium as shown.

HERMANN HUFNER.
